UNITED STATES PATENT OFFICE.

ADOLPH P. GUSTAFSON, OF CHICAGO, ILLINOIS, ASSIGNEE TO M. SCHULZ COMPANY,
OF CHICAGO, ILLINOIS.

MUSICAL INSTRUMENT.

1,403,357.

Specification of Letters Patent. Patented Jan. 10, 1922.

Application filed July 24, 1918. Serial No. 246,428.

To all whom it may concern:

Be it known that I, ADOLPH P. GUSTAFSON, a citizen of the United States, residing at Chicago, in the county of Cook and State of Illinois, have invented a certain new and useful Improvement in Musical Instruments, of which the following is a full, clear, concise, and exact description, reference being had to the accompanying drawings, forming 10 a part of this specification.

My invention relates to musical instruments and especially to pianos and player pianos.

The principal object of the invention is 15 to provide an arrangement by which accent effects can be obtained during playing.

A further object of the invention is to provide such an arrangement which shall be simple, practical, easily constructed and 20 mounted, easily taken care of and repaired, and efficient in action.

In the accompanying drawings, Fig. 1 is a vertical section of a player piano having an accent arrangement embodying my 25 invention;

Fig. 2 is a front elevation of the portion of the mechanism relating more particularly to the accent arrangement;

Fig. 3 is a view of the same looking up 30 from below;

Fig. 4 is a cross section taken on line 4—4 in Fig. 2 on an enlarged scale;

Fig. 5 is a section on line 5—5 in Fig. 4, but on a reduced scale;

Fig. 6 is a cross section on line 6—6 in 35 Fig. 5.

Fig. 7 is a view of a detail of construction;

Fig. 8 is a section on line 8—8 in Fig. 7;

Fig. 9 is a detail view. 40 In the drawings I show the upper part of a player piano having keys 1, a keyboard 2, strings 3, a piano action 4 having hammers 5, and a pneumatic action 6 for operating the piano action 4. There is also a tracker board 7 for a music sheet 8 carried by rolls 9 and 10, the tracker board 7 being connected in the usual manner by tubes 11 with the pneumatic action 6.

In accordance with my invention I provide 50 a plurality of members 12 which may be interposed between the hammers 5 and the strings 3. Each one of these members 12 is of such size or width as to come between a plurality of hammers and the strings 55 therefor, each member 12, as it were, being

interposed between a certain set or series of hammers and strings. In the drawings I show four such members 12, see for example Fig. 2, so that if eighty-eight of the notes of the piano are played by the player 60 action, as is very customary at the present time, each of said members 12 will be interposed between, or block off about one quarter or twenty-two of the piano hammers. It is not necessary to divide the eighty-eight 65 hammers into four equal parts, as it will be desirable in some instances to have more or less than an exact twenty-two present in each set or group of notes.

These members 12 are of some suitable 70 material for receiving the blows of the hammers and transmitting the same to the strings so that the sound given out by the strings will be weaker than if the hammer struck the string direct. I find felt to be 75 a satisfactory material of this character, thus when any one of the members 12 is interposed between its set or group of hammers and the corresponding strings, when any one of these hammers is actuated, the 80 strings will respond but in a weaker or quieter manner than normal so that any one of such notes being sounded will be subdued. As a result by the movement of any one or more of the members or curtains 12 in between its hammers and strings the accentuation 85 of the piece being played can be accomplished, the notes where the members or curtains 12 are interposed being struck more lightly either piano or pianissimo, whereas 90 those where the curtains are not interposed will be sounded more strongly, either forte or fortissimo.

As a preferred arrangement for actuating or manipulating these members or curtains 95 12 I show the same mounted upon a suitable supporting member 13 and arranged in connection with suitable pneumatic mechanism actuated by a plurality of buttons 14, by which any one of said curtains 12 may be actuated by pushing the proper button 14. As a preferred arrangement 100 the curtains 12 are normally in a lowered position and may be individually and independently raised by pressing the proper button 14. To such end each curtain 12 is carried by two pneumatics 15—15 which are secured to the under side of the member 13. Each pneumatic 15 is controlled by a valve 16 located in a valve chamber 17 from 110

which ducts or passages 18 extend to the interior of the pneumatic 15. The valve 16 is controlled by a small pneumatic 19 located in a pneumatic chamber 20 formed in 5 and extending longitudinally of the member 13, said member 13 being preferably made of two parts 21 and 22, mounted one above the other. The small pneumatic 19 is connected by a duct or passage 23 to a tube 10 or pipe 24, arranged outside of and at the rear of the member 13, and connected with a block 25 secured to said member 13, there being two tubes 24 to each block 25, said two tubes 24 being for the two pneumatics 15 for a single curtain 12. From each block 25 a tube or pipe 26 is extended downwardly and forwardly within the body of the player piano to the front portion of the same, as shown in Fig. 1. Connection is made by 20 each tube 26 with a duct or passage 27 in the keyboard 2 and this duct or passage is extended forwardly and connected with a flexible tubular member 28 carrying an elbow shaped member 29 (Fig. 7), which is 25 adjustable against a block 30 so that the members 29 and 30 serve as a valve and valve seat. A lever 31 is pivotally mounted at 32 and connected with the member 29 so that said member 29 may be adjusted 30 by the swinging of the lever 31. A spring 33 tends to hold the lever 31 upwardly in 35 position to close the valve 29 against its seat 30. These last mentioned parts are conveniently arranged within a recess or chamber 34 in the front portion of the keyboard. The button 14 is mounted in a small recess 35 in the keyboard and provided with a pin or rod 36 which extends down to the lever 31 so that said lever may be actuated 40 by depressing the button 14. Thus when one of the buttons 14 is actuated the corresponding lever 31 is depressed, thereby admitting air into the tube 29 whence such air passes into the tube 26, and from thence 45 through the tubes 24 and passages 23 and into the small pneumatics 19 which immediately thereupon expands because of internal pressure, the chamber 20 being a vacuum chamber connected with the wind inducing 50 apparatus of the instrument. This expansion of the pneumatics 19 causes the depression of the valves 16, thereby opening the passages 18 and establishing communication between the vacuum chamber 20 and the 55 interior of the pneumatic 15 and causing the instantaneous collapse of the latter. These two pneumatics 19 thus being simultaneously actuated will raise the curtain 12 which they control and thus this curtain 60 will be withdrawn from position between its hammers and their strings, thereby permitting such hammers to strike relatively strong and hard blows and produce relatively strong or loud notes. The four buttons 14 may obviously be controlled by the

four fingers of the player's hand so that any one or more of said buttons may be actuated and any set or series of notes controlled to produce piano or forte as desired.

As a matter of further improvement the 70 member 13 is preferably made so that it can be bodily adjusted by hand, permitting it to be so shifted as to throw all of the curtains 12 into and out of position between their hammers and strings. To such end I have 75 shown a rod 38 connected pivotally with the rear of the member 13 as at 39 and extended down so that its end is below the keyboard 2, the lower end of such rod being engaged by a lever 40 on a cross rod 41, which latter 80 is supported in bearings 42 on the bottom of the keyboard 2. A hand lever 43 is mounted at the front end of the rod 41. Thus a turning movement of the handle 43 by the hand of the operator will cause a 85 turning of the rod 41 and movement of the crank member 40 so that the rod 38 will be vertically adjusted and thereby the member 13 will be actuated so as to raise or lower the curtains 12 out of and into effective position, the member 13 being pivotally mounted at 45, as shown in Fig. 3.

It will be understood that changes and modifications may be made without departing from the spirit of the invention. 90

What I claim is:

1. The combination with the piano hammers and strings of a plurality of damping devices adapted for interposition between the hammers and strings, pneumatics on 100 which said damping devices are mounted and a support carrying said pneumatics, said support being provided with windways and valve mechanism for operating said pneumatics, said support being mounted to 105 permit it to be moved bodily so as to interpose said damping devices between the hammers and strings and to withdraw the same therefrom.

2. The combination with the piano hammers and strings of a plurality of damping devices adapted for interposition between the hammers and strings, pneumatics on 110 which said damping devices are mounted and a support carrying said pneumatics, said support being provided with windways and valve mechanism for operating said pneumatics, said support extending crosswise of the piano in front of the strings and being pivotally mounted at its front 115 edge so that its rear edge may be swung up and down to insert said damping devices between the hammers and strings and withdraw the same therefrom.

3. The combination with the piano hammers and strings of a plurality of damping devices adapted for interposition between the hammers and strings, pneumatics on 120 which said damping devices are mounted and a support carrying said pneumatics, 125

said support being provided with windways and valve mechanism for operating said pneumatics, said support being mounted to permit it to be moved bodily so as to interpose said damping devices between the hammers and strings and to withdraw the same therefrom, and means for moving said support, said means being extended forwardly to the front part of the piano near the key-board.

4. The combination with the piano hammers and strings of a plurality of curtains adapted to be interposed between said hammers and strings, a wind chest extending crosswise of the piano and supporting said curtains, said wind chest being pivotally mounted at its ends to permit it to swing up and down to shift the positions of all of the curtains simultaneously, and a plurality of pneumatic mechanisms for independently controlling the plurality of curtains, said mechanisms being supported by said wind chest.

5. The combination with the piano hammers and strings of a plurality of curtains adapted to be interposed between said hammers and strings, a wind chest extending crosswise of the piano and supporting said curtains, said wind chest being pivotally mounted at its ends to permit it to swing up and down to shift the positions of all of the curtains simultaneously, and a plurality of pneumatic mechanisms for independently controlling the plurality of curtains, said mechanisms being supported by said wind chest, and means for controlling said pneumatic mechanisms, said means extending from said wind chest downwardly and forwardly to the neighborhood of the piano keyboard.

6. The combination with the piano hammers and strings of a plurality of curtains adapted to be interposed between the hammers and strings, a plurality of sets of pneumatics carrying said curtains, there being two pneumatics for each curtain, a support to the under side of which said pneumatics are secured, said support being provided with windways and pneumatic mechanism for controlling said pneumatics, said support being pivotally mounted at its ends to permit it to swing or tilt so as to allow the curtains to be interposed between the strings and hammers and removed therefrom and means for operating said support.

7. The combination with the piano hammers and strings, of a plurality of curtains arranged to be interposed between the hammers and strings, a wind chest extending crosswise of the strings and pivoted at its ends, means for swinging said wind chest about its pivotal mounting, pneumatic mechanism mounted on the under side of said

wind chest, the latter being provided with means for controlling said mechanism, said mechanism supporting and controlling the independent curtains and pneumatic connections for said wind chest, said connections extending to the same at or near its point of pivotal support. 70

8. The combination with the piano hammers and strings, of a plurality of curtains arranged to be interposed between the hammers and strings, a wind chest extending crosswise of the strings and pivoted at its ends, means for swinging said wind chest about its pivotal mounting, pneumatic mechanism mounted on the under side of said wind chest, the latter being provided with means for controlling said mechanism, said mechanism supporting and controlling the independent curtains and pneumatic connections for said wind chest, said connections 75 extending to the same at or near its point of pivotal support, said means for controlling said wind chest comprising a rod pivotally connected with the wind chest and mechanical connections extending 80 downwardly and forwardly to the neighborhood of the piano keyboard.

9. The combination with the piano hammers and strings, of a plurality of curtains arranged to be interposed between the hammers and strings, a wind chest extending crosswise of the strings and pivoted at its ends, means for swinging said wind chest about its pivotal mounting, pneumatic mechanism mounted on the under side of said wind chest, the latter being provided with means for controlling said mechanism, said mechanism supporting and controlling the independent curtains and pneumatic actions 95 for said wind chest, said connections extending to the same at or near its point of pivotal support, and said pneumatic mechanisms each comprising a pair of hinged pneumatics having their fixed members secured to the under side of the wind chest 100 and independent controlling connections for each pair of pneumatics.

10. The combination with the piano hammers and strings, of a plurality of curtains arranged to be interposed between the hammers and strings, a wind chest extending crosswise of the strings and pivoted at its ends, means for swinging said wind chest about its pivotal mounting, pneumatic mechanism mounted on the under side of 115 said wind chest, the latter being provided with means for controlling said mechanism, said mechanism supporting and controlling the independent curtains and pneumatic actions 120 for said wind chest, said connections extending to the same at or near its point of pivotal support, and said pneumatic mechanisms each comprising a pair of hinged pneumatics having their fixed members secured to the under side of the wind 125 130

chest and independent controlling connections for each pair of pneumatics, said connections comprising pneumatic tubes extending downwardly and forwardly and 5 buttons therefor in the neighborhood of the piano keyboard.

11. The combination with the piano hammers and strings, of a plurality of curtains arranged to be interposed between the hammers and strings, a wind chest extending crosswise of the strings and pivoted at its ends, means for swinging said wind chest about its pivotal mounting, pneumatic mechanism mounted on the under side of 10 said wind chest, the latter being provided with means for controlling said mechanism, said mechanism supporting and controlling the independent curtains and pneumatic ac-

tions for said wind chest, said connections extending to the same at or near its point 20 of pivotal support, and said pneumatic mechanisms each comprising a pair of hinged pneumatics having their fixed members secured to the under side of the wind chest and independent controlling connections 25 for each pair of pneumatics, said connections comprising pneumatic tubes extending downwardly and forwardly and buttons therefor in the neighborhood of the piano keyboard, said buttons being arranged 30 to act upon a pivoted lever and the latter being arranged to control a flexible tubular member so as to open and close the same.

In witness whereof, I hereunto subscribe my name this 24th day of May, A. D., 1918. 35

ADOLPH P. GUSTAFSON.
